UNITED STATES PATENT OFFICE

HARRY BONAT, OF NEW YORK, N. Y.

HAIR PERMANENT WAVING APPARATUS

Application filed June 15, 1929. Serial No. 371,128.

This invention relates to improvements in apparatus for use in connection with the permanent waving of hair and more particularly to scalp protectors and spools for use in 5 this connection.

Heretofore scalp protectors have been made of two sections hinged together at one end and so constructed as to be clamped together at the other end. By this arrangement of the 10 clamping member, some pressure could be applied to the sections of the protector for locking hair between the same but by having a clamping member at one end only the disadvantage was encountered of unequal 15 pressure at all points along the length of the member between which the hair was locked, with resultant leakage of steam burning of hair and scalp and pulling of hair causing pain to the scalp.

20 An object of the present invention is to provide means for applying uniform pressure to a pair of members between which hair is to be locked.

A further object of the invention is to 25 provide means whereby uniform pressure may be applied through the agency of a single actuating member.

A further object of the invention is to provide resilient members for aiding in holding 30 the hair locked between the members comprising a scalp protector.

A further object of the invention is to provide means for holding a spool against movement during the winding of hair thereupon 35 and to provide means for facilitating the winding of the hair.

According to the present invention, use is made of a scalp protector composed of two members which, if desired, may be hinged 40 together at one end or which may be entirely separate members. The inner edges of each of these members is provided as is customary with strips of rubber or similar material, which strips serve to firmly grasp hair placed therebetween.

For aiding in the holding and retaining of hair between the members, use is made of springs normally forcing the rubber strips towards each other. Since it is desirable 45 that uniform pressure be applied along the

length of the pad wherein hair is locked, use is made of a locking device at each end of the pad. If so desired, these locking devices may be operated entirely separate one from the other or may be operated through the agency 55 of a single actuating member. Moreover, if desired, the locking members may be of different character such as eccentrically mounted cams, nut and screw arrangements for applying adjustable pressure, etc. 60

Other features and objects of the invention will become apparent by reference to the following detailed description read in connection with the accompanying drawings, 65 wherein

Figure 1 is a perspective view of a scalp protector embodying one modification of the present invention, such protector being in open position; and also illustrating an improved spool for use in connection with this 70 pad;

Figure 2 is a perspective view of the same protector in closed and locked position;

Figure 3 is a plan view partially in section of the device illustrated in Fig. 2; 75

Figure 4 is a section taken on the lines 4—4 of Fig. 3;

Figure 5 is a section taken on the lines 5—5 of Fig. 3;

Figure 6 is a section taken on the lines 6—6 80 of Fig. 3;

Figure 7 is a section taken on the lines 7—7 of Fig. 3;

Figure 18 is a section taken on the lines 18-18 of Fig. 16;

Figure 19 is a perspective view of one end 10 of a scalp protector with a spool in engagement therewith showing an improved method for partially locking this spool in position.

Figure 20 is a perspective plan view of a modified form of the invention wherein the 15 sections of a scalp protector are separate and unhinged when not in use;

Figure 21 is a cross-section of the device illustrated in Fig. 20 in closed position;

Figure 22 is a perspective view of a modification 20 of the invention shown in open position.

Figure 23 is a plan view partially in section of the same device in closed position.

Figure 24 is an enlarged view of one end 25 of the device.

Figure 25 is an enlarged view of the other end of the same device.

Figure 26 is a section taken on the lines 26-26 of Fig. 23.

Figure 27 is a perspective view of a further modification of the invention in disassembled arrangement.

Figure 28 is a plan view of the device illustrated in Fig. 27 in complete assembly; 35 and

Figure 29 is a section taken on the lines 29-29 of Fig. 20.

Referring now to the drawings and more particularly to Figures 1 to 7, inclusive, it 40 will be seen that the scalp protector 10 is composed of two substantially similar sections 11 and 12, which sections are constructed of flat plate-like members positioned one above the other in such a manner as to form an air space therebetween. The advantage of such air space is apparent since in the permanent waving of hair it is necessary that the minimum amount of heat be transmitted to the scalp of the patient and hence this air 50 space between the plates composing each section serves admirably for insulation purposes. The sections 11 and 12 are hinged together at one end by means of a substantially U-shaped member 13 fitting between

55 the plates of each section 11 and 12 as will be clearly seen in Figures 1 and 2. This U-shaped member 13 is provided with the perpendicular section 14 which serves as a support for one end of the spool 15 around which hair is wound. That portion of the U-shaped member 13 positioned between the plates of section 11 is provided with elongated slots 16 (one of which is indicated in Fig. 3) through which pin 17 passes. Secured between the portions of the U-shaped

member 13 is a flat bar 18 through which the pin 17 also passes. The bar 18, however, is not provided with a slot similar to slot 16 for the reason that it is desirable that the member 13 be permitted to slide between the 70 plates of section 11 relative to bar 18.

That portion of the member 13 positioned between the plates of section 12 is affixed permanently to these plates so that movement thereof is prevented. Plate 18, however, is 75 provided with a slot 19 (Fig. 3) similar to slot 16 so that plate 18 is capable of movement relative to the member 13.

To the other end of section 12 is secured a portion of a U-shaped member 20 provided with a perpendicular extension 21 which has a portion cut away as indicated at 22 for the reception of an extending pin 23 of spool 15 and which is provided with a plurality of pawl members 24 adapted for engagement 85 with a plurality of ratchet teeth 25 on the end of spool 15. The extending portion of member 20 is adapted, when the device is closed, to fit between the plates of section 11 between which is pivoted a bar 26 provided 90 at its free end with an eccentrically pivoted cam member or latch 27 which serves to lock one end of the pad in closed position as clearly shown in Fig. 2.

It will be apparent from the foregoing that 95 without further apparatus the scalp protector would be operated in the well-known manner, that is, of locking or compressing together the ends of the sections which are normally unhinged while the pressure at the 100 other end of these sections would be materially less than that at which pressure is applied. To overcome this disadvantage a member 28 similar to member 27 is eccentrically pivoted to the extending end of plate 105 18 so that pressure may be applied at this end of the device as well as at the unhinged end thereof. Due to the slots 16 in the member 13 and the slot 19 in the bar 18 it is possible to compress the sections 11 and 12 110 at their hinged end. In Fig. 3 an alternative arrangement is illustrated, wherein a nut and screw arrangement 28' is used instead of the clasp 28, by which arrangement adjustable pressure can be obtained.

For aiding in holding the hair rigidly between sections 11 and 12 use is made of a pair of T-shaped members 29 which may be composed of rubber or other suitable material. As shown in Fig. 1 the extending portion of each of these members 29 fits within or between the plates of the respective sections 11 and 12 so that when the device is closed the bar portion of each of these members is placed under compression. To aid 120 these T-shaped members 29 in firmly holding hair therebetween use is made of spring members 30, in each section 11 and 12, which rest between the inner extremity of each member 29 and uprights 31 extending between the 125 130

plates of each section. It will be apparent that when hair is positioned between the members 29 and the device closed and locked that the cooperation between the resilient material of these members 29 and the springs 30 will serve to hold the hair firmly against movement in any direction.

For aiding the winding of hair about the spool 15 when the same is engaged with the extension 21 having the pawl teeth 24, the opposite end of the spool 15 is provided with a knurled enlargement 32 which is provided with oppositely disposed knob members 33 which serve to provide a purchase for the hands of the operator winding hair.

Referring now to the embodiments of the invention illustrated in Figures 8 to 11, inclusive, it will be seen that the scalp protector is composed of parts similar to those illustrated and described in connection with the preceding figures with a few changes. In these figures parts corresponding to parts in the preceding figures will be given the same reference characters for purpose of brevity.

In order that uniform pressure at each end of the pad may be applied without recourse to separate latch members (27 and 28) provision is made in the device illustrated in Figures 8 to 11 for applying this pressure through the agency of a single manually operated actuating member. The bar 18 which normally lies between the sections of the U-shaped member 13 is provided at its free end with a pin 40 extending equi-distant on each side of the bar. Slidably mounted on one side of the scalp protector in this instance on the outside edge of section 12, is a bar 41 provided at one end with a split-wedge member 42 which is adapted to force the bar 18 outwardly by engagement between the pin 40 and the edge of section 12. This sliding movement is made possible by means of a number of slots 43 in the bar 41 through which pins 43, fastened to uprights 44 between the plates of section 12, pass. The bar 41 is normally held in retracted position relative to the bar 18 and pin 40 by means of a number of coiled springs 45 mounted between elbow members of the standards 44 and the similar members 46 fastened directly to bar 41.

For imparting sliding movement to bar 41 so that the wedge 42 causes movement of bar 18 relative to section 12, the connecting bar 26 is provided with a shoulder 47, which when this bar is moved to locking position, engages one end of bar 41 and as bar 26 is moved into locking position forces this bar 41 away from the unhinged end of the pad so that as the device is finally locked the split wedge 42 causes the application of pressure at the hinged end of the pad similar and equal approximately to the pressure applied to the unhinged end of the pad through cam

member 27. This arrangement will be apparent readily by inspection of Fig. 9.

It is sometimes desirable that pressure be applied to hair between the sections of a pad in degrees other than that which can be supplied by means of cam members as previously illustrated. For this purpose the device illustrated in Figures 12 to 14, inclusive, is made up of parts similar in each respect with the parts shown in Figures 1 to 7, inclusive, with the exception that instead of locking members 27 and 28, the ends of bars 18 and 26 are provided with screw threaded extensions 50 and 51 respectively engaged by nuts 52 and 53 respectively. When the device is closed and ready to be locked pressure of any desired degree can be applied by rotation of these nuts 52 and 53 which will bear against the edges of section 12 forcing this section inwardly relative to section 11.

A still further modification of the invention is illustrated in Figures 15 to 18, inclusive, wherein pressure may be applied to the sections of the pad uniformly along the length thereof through the agency of a single operating member positioned substantially centrally relatively to the length of the pad. As in the preceding figures the scalp protector 10 is composed of parts such as those previously described and which are numbered correspondingly herein. The bar 26 in this instance has pivotally secured on each side of the free end thereof a pair of bars 60 between the approximate center of which is secured a pin 61 passing eccentrically through a cam member 62 provided with the usual actuating latch 63. The free ends of bar 60 are reduced in size and provided with recesses 64 which are adapted to be engaged and to permit the seating of the pin 40 extending from each side of bar 18. In the operation of the device it will be apparent that after hair has been positioned between the sections of the pad the device may be locked by moving the bar 26 into its locking position between the portions of the U-shaped member 20 at the same time engaging the ends of bars 60 with the pin 40 so that this pin is seated in the slot 64. In this position the handle 63 may be moved and by reason of the cam member 62 bearing against one side of section 12 as indicated at 65 pressure will be applied to the sections since the bars 26 and 18 are in effect forced outwardly relative to section 12, thereby bringing section 11 in closer proximity to section 12.

The device illustrated in Fig. 19 consists of a standard 70 extending upwardly from one end of one section of a scalp protector which standard is provided with a cutaway portion 70 for the reception of an extending pin 72 of the usual spool around which hair is wound. A portion of the standard 71 is punched inwardly to provide a pawl member 73 while that portion of the standard im-

- mediately adjacent to this pawl member is punched outwardly to form a seat 74 for a latch member 75 pivoted to extension 76 of the standard 70. The pin 72 of the spool is 5 provided at its extremity with an enlargement 77 which when the latch 75 is rotated to rest in its seat 74 prevents the pin from being withdrawn from engagement with the pawl member 73 in a longitudinal direction.
- 10 It will be seen that the arrangement herein presented and described provides means for preventing other than longitudinal movement of the spool or upward movement of the spool relative to the pad. This arrangement is of obvious advantage since it assures proper positioning of the spool during the winding of hair thereupon.

In Figures 20 and 21 there is illustrated a device similar in all respects to the arrangement illustrated in the Figures 1 to 7, inclusive, with the difference that section 12 instead of being secured to the member 13 is an entirely free and separate member which can be, however, securely locked to the section 11 25 and when so locked can be operated in such a manner as to apply uniform pressure to hair between these two sections.

In Figures 22 to 26 inclusive there is illustrated a modification of the present invention 30 which consists of a relatively narrow section 80 in hinged relation to a wider section 81. These two sections are made up of spaced members between which are inserted resilient strips of material 82 in the shape of substantially a T. The section 81 is provided at one end with an upright standard 83 having a cutaway portion 84 for the reception of a pin on the end of a spool and also provided with a pawl member 85 for engagement with ratchet teeth on the spool. To the other end of section 81 is secured in any desired manner an upright support member 86 for supporting the free end of the spool upon which hair is wound. It will be noted 45 that these two sections are connected by means of a bar 87 pivotally secured as at 88 to section 80 and slidably secured by means of pin 89 and slot 90 to section 81. To the other end of section 80 is pivotally secured 50 a connecting member or bar 91, the free end of which is provided with a slot 92.

Slidably mounted within the section 81 is a bar 93 provided at substantially its mid-point with a rack 94 engaged by a pinion 95 55 rotating about shaft 96 and securely fastened to actuating clamp 97. As will be seen by reference to Fig. 23, that end of bar 93 adjacent to the hinged connection between the sections is provided with a recess 98 which 60 has an outward slope as indicated at 99. This portion of the bar 93 passes through a slot 100 (Fig. 24) so that as bar 93 is moved away from or inwardly relative to the end of section 81, the inclined portion 99 causes bar 87 to be pulled toward section 81.

At one end of section 81 is provided a receiving clasp member 101 which serves to hold the connecting bar 91 in place when the device is closed. For locking it in place and applying pressure to pull the sections together, one end of bar 93 is provided with a tapered edge 102 which serves to enter slot 92 and by contact with the outer edge of this slot pull the two sections together.

From the foregoing it will be seen that the operation of this embodiment is substantially as follows. Hair to be waved is placed between the two sections which are closed by moving them about their pivotal point and engaging the bar 91 within the clasp 101. By manipulating the handle 97 the bar 93 is moved longitudinally of section 81, one end of it through the agency of the tapered surface 99 pulling the pivoted ends of the sections together while the other end through the agency of tapered surface 102 engaging slot 92 pulls the other ends of the sections together simultaneously. By this arrangement a single actuating member serves to exert or cause to be exerted uniform pressure upon hair situated between the sections along the entire length of the sections.

In Figs. 27 to 29 inclusive a still further modification of the invention is shown wherein the device is composed of two similar sections 105 and 106, the section 105 being secured to each of a pair of channel members 107. To one of these channel members 107 is pivotally secured a bar 108 which bar is bent out of alignment in its intermediate portion and provided with an opening in substantially its mid-point through which is screw threaded a nut 109 provided with a knurled thumb screw 109'. To the inner end of nut 109 is secured an arcuate shaped member 110 which is positioned with its outer surface parallel to the outer surface of bar 108 by means of a pair of pins 111. The two sections 106 are provided as is usual with strips of resilient material 112 of shape similar to that heretofore described.

In the operation of this device, hair may be placed between the two sections 105 and 106, section 106 being permitted to rest within the confines of the channel bars 107. In this position the arcuate shaped member 110 rests against the outer edge of section 106 so that by rotation of thumb screw 110 the section 106 can be forced firmly against or as closely as possible to section 105.

From the foregoing it will be seen that the present invention provides novel and efficient means for applying uniform pressure to hair between the sections of a scalp protector and furthermore that the invention provides means whereby this pressure may be applied either at each end of the scalp protector separately or by means of a single actuating member which operates in such a manner as to apply pressure simul-

taneously and uniformly along the length of the pad. It is to be understood that the present invention is not to be limited to the illustrated embodiments but is to be limited 5 only by the scope of the following claims.

I claim:

1. A device of the character described comprising a pair of sections, means for connecting said sections together and means 10 forming a part of the device for applying positive pressure at each end of the device for forcing said sections together.
2. A device of the character described comprising a pair of sections, a hinged connection for one end of said sections, means 15 for connecting the other ends thereof and means forming a part of the device for applying positive pressure at each end of the device to force the sections together.
- 20 3. A device of the character described comprising a pair of sections, means for connecting said sections and means at each end of said sections for drawing them together uniformly along the length thereof, said 25 means being individually operable.
4. A device of the character described comprising a pair of sections pivotally connected at one end, a lock member for connecting the other ends of the sections and 30 means for applying at each end variable pressure to draw said sections together.
5. A device of the character described comprising a pair of sections each composed of spaced plates, resilient insets between said 35 plates and extending between the inner edges of the sections and resilient members normally forcing said insets toward each other.
6. A device of the character described comprising a pair of sections, means for connecting the ends of said sections together, 40 pressure members for forcing said sections together at each end thereof, and a single actuating means for exerting said pressure.

In testimony whereof, I have signed my 45 name to this specification.

HARRY BONAT.
